US0D1033248S

(12) **United States Design Patent** (10) **Patent No.:** **US D1,033,248 S**
(45) **Date of Patent:** **** Jul. 2, 2024**

(54) **CONNECTION SEAT FOR STAIR
MEASURING RULER WITH LIMITER**

(71) Applicant: **Yunan Liu**, Guangzhou (CN)

(72) Inventor: **Yunan Liu**, Guangzhou (CN)

(**) Term: **15 Years**

(21) Appl. No.: **29/927,039**

(22) Filed: **Feb. 2, 2024**

(51) **LOC (14) Cl.** **10-04**

(52) **U.S. Cl.**

USPC **D10/74**

(58) **Field of Classification Search**

USPC D10/64, 65, 70, 71, 74, 103

CPC E04F 21/26; G01B 3/28; G01B 3/08

(57) **CLAIM**

The ornamental design for a connection seat for stair measuring ruler with limiter, as shown and described.

DESCRIPTION

FIG. 1 is a front perspective view of a connection seat for stair measuring ruler with limiter showing my new design; FIG. 2 is a rear view thereof; FIG. 3 is a front view thereof; FIG. 4 is a left side view thereof; FIG. 5 is a right side view thereof; FIG. 6 is a top plan view thereof; FIG. 7 is a bottom plan view thereof; FIG. 8 is a rear perspective view of the connection seat for stair measuring ruler with limiter thereof; FIG. 9 is a rear perspective view of the connection seat for stair measuring ruler with limiter shown in an exploded view; FIG. 10 is a rear perspective view of the connection seat for stair measuring ruler with limiter shown in another configuration of use; FIG. 11 is a rear view of the connection seat for stair measuring ruler with limiter shown in a state of use; and, FIG. 12 is a rear view of the connection seat for stair measuring ruler with limiter shown in another state of use. The broken lines in the drawings depict portions of the connection seat for stair measuring ruler with limiter that form no part of the claimed design.

1 Claim, 10 Drawing Sheets
